(57) **CLAIM**

The ornamental design for a support for mobile electronic device as shown and described.

DESCRIPTION

FIG. 1 is a perspective view of a support for mobile electronic device, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, showing the support for mobile electronic device in an in-use state;

FIG. 10 is a perspective view thereof, shown in a first open position when in use with a casing for mobile electronic device; and,

FIG. 11 is a perspective view thereof, shown in a second open position when in use with a casing for mobile electronic device.

The broken lines in FIGS. 1–8 depict portions of the support for mobile electronic device that form no part of the claimed design. The broken lines showing an electronic device case in FIGS. 9–11 illustrate environmental subject matter, and form no part of the claimed design.
